CHARGING DEVICE

Filed March 1, 1930

UNITED STATES PATENT OFFICE

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY

CHARGING DEVICE

Application filed March 1, 1930. Serial No. 432,389.

This invention relates to charging devices, but more particularly to a charging device adapted for depositing explosive material in a submerged drill hole.

5 One of the objects of the invention is to enable the explosive material to be conveniently deposited and compressed in the bottom of a submerged drill hole and another object is to permit of relative pivotal movement between various elements comprising the charging device in order to prevent binding of the device in a drill hole, as for instance, a drill hole in which a portion or portions incline from the true course.

15 Other objects will be in part obvious and in part pointed out hereinafter.

In the accompanying drawings illustrating the invention and in which similar reference characters refer to similar parts,

20 Figure 1 is an elevation of the charging device constructed in accordance with the practice of the invention and showing the manner in which it may be lowered into the drill hole,

25 Figure 2 is a sectional elevation of the charging device, and

Figure 3 is a sectional elevation of the charging device illustrating the manner in which the container or tube for explosive material may adjust its position with respect to the handle extension.

Referring to the drawings, and at first more particularly to Figure 1, the charging device which is designated generally by A is shown suspended from a derrick B mounted upon a scow or drill barge C supported by the water D.

The barge C may be anchored in any suitable manner, and suspended therefrom is a 40 guide frame E consisting of a pair of parallel members F which extend downwardly to a point near the bottom of the stream, such as the silt G, which overlies the rock formation H wherein a hole J has been drilled.

45 The lower ends of the members F are in this instance held in spaced relation with respect to each other by a cross head K to which is attached a sand pipe L. The sand pipe L is shown extending through the silt G and seats with its lower end against the rock H.

to prevent the entrance of silt and débris into the drill hole during the drilling operation.

The loading device constructed in accordance with the practice of the invention comprises a tube O, the interior of which forms a chamber P for explosive material Q. At the rear end of the tube O is a head R which may be secured to the tube in any suitable manner and said head R has a socket S preferably of partly spherical form for the reception of a ball T carried by the end of a handle extension U whereby the loading device A may be manipulated.

In order to eject the explosive material 65 from the chamber P the said chamber is provided with a plunger V having in this instance a flexible rod W which extends through a bore X in the handle extension U. The rod W carries on its upper or free end a 70 link Y to which may be attached a cable or rope Z whereby the device A may be lowered into the drill hole J or removed therefrom.

The handle extension U and the rod W may be of any suitable length, depending upon 75 the depth of the water overlying the rock H, and in this instance the bore X serves as a passage through which fluid under pressure, as for instance, water or air, may be conveyed to the chamber P for actuating the 80 plunger V. Such pressure fluid is preferably admitted into the upper end of the extension U through a connection b which may lead from a suitable source of supply and having a controlling means, such as a valve 85 c, interposed therein for controlling the admission of fluid into the bore X and thus also into the chamber P.

To the end that the plunger V may be prevented from being completely forced out of the open end of the chamber P the rod W is provided with an adjustable clamp collar d which may be moved along the length of the rod W. The collar d may be clamped to the 90 rod W in any desired position to either prevent the plunger V from being moved out of the chamber P or for holding it in any intermediate position in the chamber.

In the front end of the tube O is a slot e to receive an ignition wire f which may lead 95

from a source of electrical energy, such as a battery (not shown), to a detonator *g* in the explosive material *Q*. The wire *f* may serve as a means for maintaining the explosive material within the chamber *P*. By securing the wire to the foremost section of the explosive material and thereafter maintaining the said wire reasonably taut the explosive material will be securely held in the chamber *P* during the operation of entering the tube into the drill hole.

Additional means, however, such as a wedge *h*, may be provided for retaining the explosive material in the chamber *P*. The wedge *h* may be inserted in the front end of the tube *O* to press the foremost section of the explosive material lightly against the wall of the chamber *P*, and upon the expulsion of the explosive material the wedge will also be expelled from the tube along with the explosive.

As will be readily understood from the foregoing description, the tube *O*, together with the head *R*, are capable of universal movement with respect to the extension *U*. This is a desirable feature in devices of this character since it enables the tube *O* which is of larger diameter than the extension to readily adjust its position in an inclined drill hole.

In known devices of this character in which the tube and the handle extension are rigidly connected to each other considerable trouble is often encountered in depositing the explosive charge in the bottom of a drill hole where, owing to irregularities in the rock, the drill steel which, during the course of the drilling operation, deflects from the desired course so that the hole becomes inclined with respect to the drilling apparatus. The principal difficulty in charging such holes is that the tube, which is of necessity only of slightly smaller diameter than the drill hole, binds on the sides thereof as does also the handle extension. It therefore frequently becomes necessary to eject the explosive material from the chamber while the tube is still a considerable distance from the bottom of the hole. Obviously, when thus ejected it is not possible to compress the charge in the bottom of the drill hole.

Although flexibility is an extremely desirable feature in chargers of this type, it is however essential that the tube *O* be maintained in substantially coaxial alignment with the handle extension *U* during the time the device *A* is being lowered into the drill hole and until at least the end of the tube *O* has been entered into the drill hole.

In order to assure these relative positions of the tube *O* and the extension, the plunger *V* is provided with a stem *j* which extends rearwardly of the plunger and may be attached to the rod *W*. The stem *j* is of such length that when the plunger *V* is fully re-

tracted in the chamber *P*, said stem will extend into the bore *X* of the handle extension *U* to lock the tube *O* and the handle extension against any relative movement other than rotational. The handle extension and the tube will then be held in coaxial alignment and the charging device will, in effect, be rigid so that the tube *O* may be readily inserted into the sand pipe *L* and thus into the drill hole *J*.

After the tube *O* has entered the drill hole, the collar clamp *d* may be moved along the rod *W* to a distance from the end of the handle extension *U* slightly in excess of the length of the stem *j*. This will permit the stem *j* to be removed from the bore *X*. The tube will then be free to follow the course of least resistance through the drill hole.

The pressure required for moving the stem out of the bore *X* may be applied either manually by pressing on the rod *W* or pressure fluid may be admitted from the conduit *b* into the bore *X*. When pressure fluid is used for this purpose such pressure fluid will act against the stem *j* and against the rear end of the plunger *V* and will move the plunger and stem downwardly until the collar clamp *d* again seats against the end of the handle extension *U*. The device may then be readily lowered until the end of the tube *O* seats against the bottom of the drill hole *J*.

When the tube *O* reaches this position the collar clamp *d* may be released. Fluid under full line pressure may then be admitted into the chamber *P* to move the plunger *V* downwardly for expelling the explosive charge from the chamber *P* and to compress it in the bottom of the drill hole *J*. After the explosive material has been expelled from the chamber *P*, the entire device may again be lifted from the drill hole by means of the cable *Z*.

The stem *j* may, if desired, consist of two portions *k* and *o* of different diameters.

When so constructed the portion *k* may be of larger diameter than the portion *o* which fits into the bore *X* and the head *R* may be provided with a suitable bore *p* to accommodate the portion *k* of the stem *j*. Preferably the portions *k* and *o* are provided with tapered seating surfaces *q* and *r* respectively to enable said portions to readily enter their respective bores.

The plunger *V* may serve both as a means for ejecting the explosive material *Q* from the chamber *P* and also as a means for tamping the explosive material in the bottom of the drill hole. When serving in the latter capacity the plunger *V* may be held in the extended position, that is, in the position illustrated in Figure 2 in which the end of the plunger protrudes from the tube *Q*. The plunger *V* may be readily held in this position by the pressure fluid used for moving it downwardly and its movement in this direc-

tion will of course be limited by the link Y which, when the plunger V lies in the foremost position in the tube, will seat against the collar clamp d.

5 When using the device as a tamper the entire device is of course reciprocated bodily in the drill hole by the operator who may grasp the handle extension for this purpose. In moving the tube O back and forth in the 10 drill hole for the purpose of compressing the explosive material therein it is quite possible, and in fact it frequently happens, that detritus lodged on the wall of the drill hole may become loosened by the tube O.

15 Unless removed such detritus will accumulate in the space between the tube O and the wall of the drill hole J and will exert a binding action on the tube which will greatly interfere with the free movement of the tube. Moreover, in locations where the sand 20 pipe L seats on an inclined rock surface it is also possible for silt to drop into the drill hole and accumulate therein to an extent which will interfere seriously with the tamping 25 movement of the device.

As may be readily understood, it is therefore desirable that the drill hole be thoroughly flushed to remove dirt and cuttings therefrom. To this end the tube O is provided 30 with a series of ports s which may be arranged in the same transverse plane and are preferably so located in the tube that when the plunger V is fully extended, that is, when it lies in its foremost position, said ports s will 35 be uncovered by the plunger V. In this way, when the plunger V is forced forwardly to eject the explosive material from the chamber P the ports s will be uncovered so that pressure fluid may escape from the chamber 40 P into the drill hole. Any loose material, such as silt or cuttings, which may tend to precipitate in the drill hole will then be flushed through the sand pipe L, thus assuring 45 free movement of the device for tamping the explosive material in the drill hole.

By locating the ports s in the manner described the movement of the plunger V within the chamber P during the tamping operation will be to some extent cushioned, 50 since, when the device is dropped on the charge to compress it, the plunger V is capable of some slight degree of movement in the direction of the ports s which it may overrun upon each thrust of the plunger V 55 against the explosive charge.

I claim:

1. A charging device comprising a tube adapted to be inserted into a drill hole and having a chamber for explosive material, a 60 plunger for ejecting the explosive material from the chamber, a handle extension for the tube and being pivotally connected thereto, and means for holding the tube and the handle extension against relative pivotal 65 movement.

2. A charging device comprising a tube adapted to be inserted into a drill hole and having a chamber for explosive material, a plunger for ejecting the explosive material from the chamber, a handle extension for the 70 tube and being pivotally connected thereto, and locking means for maintaining the tube in axial alignment with the handle extension.

3. A charging device comprising a tube adapted to be inserted into a drill hole and having a chamber for explosive material, a plunger for ejecting the explosive material from the chamber, a handle extension for the 75 tube and being pivotally connected thereto, and locking means associated with the 80 plunger for holding the handle extension and the tube against relative pivotal movement.

4. A charging device comprising a tube adapted to be inserted into a drill hole and having a chamber for explosive material, a 85 plunger for ejecting the explosive material from the chamber, a handle extension having a bore and being pivotally connected to the tube, and a stem on the plunger and movable into the bore to hold the tube and the handle 90 extension against relative pivotal movement.

5. A charging device comprising a tube adapted to be inserted into a drill hole and having a chamber for explosive material, a plunger for ejecting the explosive material 95 from the chamber, a handle extension for the tube and having a universal connection with said tube, said handle extension having a bore, a stem on the plunger to engage the bore for holding the tube in axial alignment with 100 the handle extension, and means for moving the stem out of the bore to permit of universal movement of the tube with respect to the handle extension.

6. A charging device comprising a tube 105 adapted to be inserted into a drill hole and having a chamber for explosive material, a plunger for ejecting the explosive material from the chamber, a handle extension having a universal connection with the tube, said 110 handle extension having a bore therein, a stem associated with the plunger and adapted to extend into the bore to hold the tube axially aligned with respect to the handle extension, and means for introducing pressure fluid into 115 the bore to act against the stem and the plunger for moving said stem out of the bore, thereby permitting the tube to assume an inclined position with respect to the handle extension.

7. A charging device comprising a tube 120 adapted to be inserted into a drill hole and having a chamber for explosive material, a plunger for evacuating the explosive material 125 from the chamber, a handle extension having a universal connection with the tube, said handle extension having a bore therein, a stem associated with the plunger and adapted to be extended into the bore to hold the tube axially aligned with respect to the 130

handle extension, a flexible rod extending through the bore and connected to the stem for moving the stem into the bore, and a connection leading from a source of pressure fluid supply and connected to the handle extension for introducing pressure fluid into the bore to act against the stem and the plunger for removing the plunger from the bore to permit the tube to assume an inclined position with respect to the handle extension and also for evacuating the explosive material from the tube into the drill hole.

8. A charging device comprising a tube adapted to be inserted into a drill hole and having a chamber for explosive material, a pressure actuated plunger in the chamber for ejecting the explosive material from the chamber, and a port in the tube adapted to be uncovered by the plunger to permit the escape of pressure fluid from the chamber for flushing the drill hole.

9. A charging device comprising a tube adapted to be inserted into a drill hole, and having a chamber for explosive material, a pressure fluid actuated plunger in the chamber for ejecting the explosive material from the chamber and for compressing the explosive material in the drill hole, a handle extension pivotally connected to the tube and having a bore for conveying pressure fluid into the chamber, and ports in the tube near the front end thereof and adapted to be uncovered by the plunger to permit the escape of pressure fluid from the chamber for flushing the drill hole.

In testimony whereof I have signed this specification.

CHARLES C. HANSEN.
